UNITED STATES PATENT OFFICE.

WILLIAM W. DEAN, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

TELEPHONE SYSTEM.

1,120,605.

Specification of Letters Patent.

Patented Dec. 8, 1914.

Application filed March 12, 1908. Serial No. 420,546.

To all whom it may concern:

Be it known that I, WILLIAM W. DEAN, a citizen of the United States, residing at Elyria, in the county of Lorain and State 5 Ohio, have invented a certain new and Improved Telephone System, (Case 1,) of which the following is a full, clear, concise, and exact description, reference being had to the accompanying drawings, forming a 10 part of this specification.

The object of my invention is to produce a telephone system in which it will be impossible for the operator, through accident or otherwise, to connect the ringing generator in circuit with a busy line.

In the use of telephone systems generally in the past, especially in connection with multiple switchboards, it has been possible for connection to be made by means of one 20 of the multiple jacks with two connected lines when these lines were connected through other jacks and suitably connecting circuits for conversation, and it has been possible by the extra connection thus made 25 to send ringing current out on to the busy line with the result that often serious injury has been done to the persons using the telephones.

It is an object of my invention to so connect the apparatus at the exchange that it will be impossible to complete a circuit from the ringing generator through the connecting apparatus to a line which is in talking condition or, as it is commonly called, busy.

35 My invention consists in equipping one of the relays of each of the cord circuits used for connecting the lines for conversation with extra contacts through which the generator circuit is closed. These relays 40 are so associated with the calling plugs of the cord pair that when one of said plugs is inserted in a jack connected to a busy line, the relay is energized and connection between these extra contacts is broken, thus 45 interrupting the connection of the ringing generator to that particular cord pair. Another result secured by my invention is that when a cord pair is used for connecting two subscribers for conversation and the connection is complete with the exception that 50 the called subscriber has not responded, the operator may ring the desired substation until such subscriber does respond, but as soon as he removes his receiver from the

switch hook a relay connected with the cord 55 pair is energized and by means of contacts controlled thereby the circuit from the ringing generator to such cord pair is broken and thus the operator is prevented from again sending ringing current through the 60 apparatus at the substation connected with the calling plug.

Referring to the drawings, I have shown two party lines extending by their limbs 1, 2 and 3, 4 from a plurality of substations 65 A, A', A², A³ and C, C', C², C³ to multiple jacks J, J' and J², J³ at an exchange. These line circuits are identical, as are the substations connected therewith, and hence detailed description of but one circuit and one 70 substation is needed.

The line wires 1, 2 are connected to armatures 56 and 57 of cut-off relay R and connection is normally made through such armatures by contacts 58 and 59, through line 75 relay R' and wires 50 and 51 with the terminals of the main battery B. The relay R' is provided with an armature 66, adapted when attracted to close the contact 67 and thus to complete a circuit between wires 50 80 and 51 through line lamp 68. Armatures 56 and 57 are adapted to be operated by relay R, one terminal of which is connected by wire 69 with the rings 60 and 61 of jacks J and J', while the other terminal of the 85 winding of this relay R is connected by wire 51 with the grounded terminal of battery B.

The substation A' is equipped with the transmitter 13 connected through the usual hook switch with line wire 1 and with the 90 terminal of this transmitter is connected the juncture of windings 14 and 16, which are two windings of a Wheatstone bridge arrangement used for supplying current to the receiver 18. This Wheatstone bridge 95 consists of the inductive windings 16 and 17 and the non-inductive windings 14 and 15, so connected and of such resistance that the receiver 18 is connected in bridge between the points of juncture of the windings 15 100 and 16 and 14 and 17, which points are of equal potential, when direct current flows from the transmitter 13 through these connected windings and back to line wire 2. As a result of the impedance value of the 105 windings 16 and 17, however, when voice currents flow through this same circuit they are practically all directed through the re-

ceiver 18. A ringer 12 in circuit with condenser 11 is also provided in bridge of the line wires 1 and 2.

As a result of the construction described above, when the receiver is removed from the switch hook at the substation A', the relay R' is energized, current taking the following path: battery B, wire 50, relay R', contact 58, armature 56, wire 1, transmitter 13, thence through the bridge windings back to wire 2, armature 57, contact 59, wire 51, to battery B, as result of which the relay R' is energized and a circuit closed through the line lamp 68, as follows: battery B, wire 50, armature 66, contact 67, lamp 68, wire 51, back to the battery B. In response to this signal an answering plug of the cord pair is inserted in the answering jack with the result that precisely the same operation 20 takes place as illustrated for the calling plug P, which is as follows: The sleeve relay S connected with the plug is energized by the following circuit: battery B, wire 50, wire 43, wire 45, relay S, wire 44, cord strand 6, sleeve 63 of the plug P, ring 60, wire 69, relay R, wire 51, back to battery B. As result of this the relay R is energized and armatures 56 and 57 are removed from contacts 58 and 59, respectively, cutting off connection between the battery B and line wires 1 and 2. The several ringers located at the different substations may be of any well known type adaptive to selective signaling, that form of ringer known 35 as the harmonic ringer being particularly available for this purpose.

The cord circuit shown for connecting lines for conversation consists of tip and sleeve strands 5, 7, 9 and 6, 8, 10, respectively, terminating in answering and calling plugs P² and P. Strands 5, 6 terminate in tip and sleeve 62 and 63 respectively, of calling plug P, while the strands 9, 10 terminate similarly at the answering plug P². 40 Besides the relay S associated with the sleeve strand as above described, there is a second relay T associated with the tip strand, the two relays coöperating to effect the supervisory signaling for the calling 45 plug. Similar relays are associated with the tip and sleeve strands of the answering plug, but since the supervision of the connection is not a feature of this invention, no reference is made to the signaling relays 50 except in so far as they are concerned in the control of the circuits forming the subject matter of this invention.

When the relay S is energized as described above by the plug P being inserted 60 in the jack J, a signaling circuit is closed as follows: battery B, wire 50, wire 43, wire 45, contact 35, armature 34, wire 48, contact 37, armature 36, supervisory lamp 38, wire 41, wire 42, back to battery B. The relay 65 S also closes a second circuit as follows:

from the tip strand 7 through wire 39, armature 32, contact 33, relay T, wire 41, wire 42 to the grounded terminal of battery B, as result of which when the line wire 2, which is at this time connected to the cord strand 7, is connected with the live side of the battery, the relay T will be energized. This is accomplished when the receiver is removed from the switch hook at one of the substations, current taking the following path: battery B, wire 50, wire 43, wire 45, relay S, wire 44, cord strand 6, sleeve 63, contact spring 53, line wire 1, transmitter 13, line wire 2, jack spring 52, tip 62, cord strand 5, key spring k⁴, contact 25, cord strand 7, wire 39, armature 32, contact 33, wire 40, relay T, wire 41, wire 42, back to battery B. This attracts armatures 36 and 29, breaking the supervisory circuit and also breaking a second circuit which was closed between the armature 29 and contact 31. This circuit was effective before the subscriber answered in sending signaling current on to the line as follows: The ringing keys k, k', k², k³ are connected through their normally open contacts 21, 22, 23 and 24 with the ringing generators G, G', G², G³, adapted to selectively ring the several substations connected to the different lines. The ringing keys k, k', k² and k³ are mechanically connected by means not shown, with the key springs k⁴ and k⁵, so that when operated to put ringing current on to the line the cord strands are opened to prevent the ringing current flowing back into the answering end of the cord. Assuming that current from the generator G' is adapted to operate the ringer 12, the ringing key k' is operated, and if the receiver 18 has not been removed from the switch hook a 100 circuit would be completed as follows: ringing generator G', contact 22, spring k', wire 29, contact 31, armature 29, wire 49, cord strand 5, tip 62, jack spring 52, line wire 2, condenser 11, ringer 12, line wire 1, jack 105 spring 53, sleeve 63, ring 60, wire 69, relay R, wire 51, ground g, ground g', back to generator G'. From the circuit just traced it appears that when relay T is energized 110 the connection of the ringing generator to the cord circuit is interrupted and that the operation of the keys k, k', k², k³ will not produce any effect upon the cord circuit or the line with which the cord circuit may be connected. When the relay T is energized 115 the armature 29 engages contact 30, establishing a connection between cord strands 5 and 7, which connection effects the holding of the relay T if one of the ringing keys is energized while the line connected with the 120 calling plug is busy. This circuit is traced as follows: battery B, wire 50, wire 43, wire 45, relay S, wire 44, sleeve strand 6, sleeve 63, jack spring 53, line wire 1, transmitter 13, line wire 2, jack spring 52, tip 125 130

62, tip strand 5, wire 49, armature 29, contact 30, wire 70, cord strand 7, wire 39, armature 32, contact 33, wire 40, relay T, wire 41, wire 42, back to battery B.

5 In the drawings the apparatus is indicated in the position it would assume if the substation C³ were connected by means of the upper cord circuit with substation A' and both parties were engaged in conversation.

10 A second cord circuit is shown in the lower part of the drawing, which is a duplicate of the upper cord circuit in all respects, and this cord circuit is represented as connected with the line 1, 2, which, as described above, is represented as busy.

15 Whether the answering plug P³ of the lower cord circuit is in an answering jack of some other line or whether it is entirely disconnected is immaterial to the operation of the

20 relay T^a, which is immediately energized upon the insertion of the plug P' into the jack J' connected with the busy line 1, 2. This energizing circuit may be traced as follows: battery B, wire 50, wire 45^a, relay

25 S^a, wire 44^a, cord strand 6^a, sleeve 65, jack spring 55, line wire 1, transmitter 13, line wire 2, jack spring 54, tip 64, cord strand 5^a, key spring k^{4a}, contact 25^a, cord strand 7^a, wire 39^a, armature 32^a, contact 33^a, wire 40^a, 30 relay T^a, wire 41^a, wire 42, back to battery B.

After being energized, the relay T^a is held against release by the opening of the key k^{4a}, by means of a circuit as already described, which is identical with that shown for the cord circuit in the upper part of the drawings. The ringing key k^a is shown as operated in the lower cord circuit, but as result of the operation of the armature 29^a the 40 circuit is interrupted between armature 29^a and contact 31^a, and hence connection between the generator G and the tip 64 is interrupted and ringing current can not be sent from the generator G to any of the 45 substations connected with the line 1, 2. Since keys k^a, k^{4a}, k^{2a}, k^{3a} are all connected through the same circuit by wire 20^a to the tip 64, it will be understood that the operation of the relay T^a serves in similar manner to effectually disconnect all of the ringing generators from the calling plug. By this means I have made it impossible for an operator to send ringing current out on a busy line, and I have thus made it impossible to send ringing current through 50 the receiver at any of the substations where such receiver is being used.

Among the desirable results of my invention may be mentioned the elimination 60 of injury to the subscriber's ear due to the ringing current in the receiver and also the elimination of a large part of the danger due to high tension signaling currents being applied to telephone instruments while the 65 subscriber is in proximity to the connections

and liable to receive a shock from such current through careless handling of the telephone connections.

While I have shown my invention in the particular embodiment herein disclosed, I 70 do not limit myself to this modification, but claim broadly any equivalent construction for securing the same results.

What I claim is:—

1. In a telephone system, a plurality of 75 lines extending by their limbs from substations to an exchange, switching mechanism at the exchange having an answering and a calling end for connecting such lines for conversation, a source of signaling current 80 at the exchange, switch contacts and circuit connections for connecting said source to said system, contacts in said switching mechanism between the answering end and the circuit connections of the source of signaling current, means for preventing the sending of signaling current from such source to a line already in talking communication, and a circuit independent of said last named 85 contacts for locking said means. 90

2. In a telephone system, a plurality of 95 lines extending by their limbs from substations to an exchange, switching mechanism at the exchange having an answering and a calling end for connecting such lines 100 for conversation, a source of signaling current at the exchange, switch contacts and circuit connections for connecting said source to said system, contacts in said switching mechanism between the answering end and the circuit connections of the source of signaling current, a relay for preventing the sending of signaling current from such source to a line already in talking communication, and a circuit independent of said last named contacts for locking 105 said relay.

3. In a telephone system, a plurality of 110 lines extending by their limbs from substations to an exchange, a cord circuit at the exchange for connecting said lines together, a source of signaling current at the exchange, circuit connections and switch contacts for connecting said source to the system, a switch adapted to sever said cord circuit when the signaling current is connected to said system, means for preventing the sending of signaling current from said source to a line already in talking communication, and a locking circuit for said preventive means independent of said switch. 115

4. In a telephone system, a plurality of 120 lines extending by their limbs from substations to an exchange, a cord circuit at the exchange for connecting said lines together, a source of signaling current at the exchange, circuit connections and switch contacts for connecting said source to the system, a switch adapted to sever said cord circuit when the signaling current is con- 125 130

5. nected to said system, a relay for preventing the sending of signaling current from said source to a line already in talking communication, and a locking circuit for said relay 5 independent of said switch.
6. In a telephone system, the combination with a cord circuit, of a ringing key therefore, a subscriber controlled supervisory relay, said ringing key being connected with a strand of the cord circuit through normal contacts of said supervisory relay, substantially as described.
7. In a telephone system, the combination with a cord circuit, of a ringing key therefor having a plurality of contacts normally in series with a portion of a talking strand of the cord circuit, a subscriber controlled supervisory relay having contacts in the circuit of said key, said relay being actuated during conversation to disconnect said series key contacts from the talking circuit.
8. In a telephone system, the combination of a main station, a plurality of substations and subscribers' lines connecting the substations and main station, a cord circuit at the main station for connecting subscribers' lines together, means including plugs and jacks for connecting the cord and lines together, said cord including two strands, one connected to the tips of the plugs and another to the sleeves of the plugs, a subscriber controlled relay connected to the tip strand of said cord, a source of ringing current, a ringing key controlling the same, said ringing key being connected with a strand of the cord circuit through normal contacts of said supervisory relay.
9. In a telephone system, the combination with a main station, a plurality of substations, telephone lines connecting the substations to the main station, a cord circuit at the main station for connecting said lines together, switching means including plugs and jacks for connecting the cord to said lines, one of the strands of the cord circuit being connected to the tips of the plugs, a source of ringing current, a ringing key controlling the same, said ringing key having a plurality of contacts normally in series with a portion of a talking strand of the cord circuit, a supervisory relay connected to the tip strand of the cord circuit and having contacts in the circuit of said key, said relay being actuated during conversation to disconnect said series key contacts from the talking circuit, substantially as described.
10. In a telephone system, a plurality of telephone lines extending by their limbs from sub-stations to an exchange, switching mechanism at the exchange for connecting such lines for conversation, a supervisory relay in such exchange switching mechanism, a source of current at said exchange for signaling the sub-stations, circuit connections for connecting said source to said telephone lines, contacts in said circuit connections directly controlled by said supervisory relay and operated when the switching mechanism is connected to a busy line to automatically prevent the connection of the source of ringing current to said busy line.
11. In a telephone system, a plurality of telephone lines extending by their limbs from sub-stations to an exchange, switching mechanism at the exchange for connecting such lines for conversation, supervisory means in such exchange switching mechanism, a source of current at the exchange for signaling the sub-stations, circuit connections for connecting said source to said telephone lines, contacts in said connections directly controlled by said supervisory means and operated when the switching mechanism is connected to a busy line to prevent the connection of the source of ringing current to said busy line.
12. In a telephone system, a plurality of telephone lines extending by their limbs from substations to an exchange, switching mechanism for connecting said lines, a source of signaling current for signaling said substations, a ringing key controlling the source of signaling current, circuit connections therefor normally connected to said switching connections, and supervisory means operating on connection of the switching mechanism to a busy line to automatically disconnect the source of signaling current.
13. In a telephone system, a plurality of telephone lines extending by their limbs from substations to an exchange, switching mechanism for connecting said lines, a source of signaling current for signaling said substation, a ringing key controlling the source of signaling current, circuit connections therefor normally connected to said switching connections, and supervisory means operating on connection of the switching mechanism to a busy line to automatically disconnect the source of signaling current and prevent the application of signaling current to a line already in talking condition.
14. In a telephone system, a plurality of telephone lines extending by their limbs from substations to an exchange, switching mechanism for connecting said lines, a source of signaling current for signaling said sub-stations, a ringing key for said source normally connected to said switching

mechanism, and supervisory means operated on connection of the switching mechanism with a busy line to automatically disconnect the source of ringing current.

- 5 15. In a telephone system, a plurality of telephone lines extending by their limbs from substations to an exchange, switching mechanism for connecting said lines, a source of signaling current for signaling 10 said substations, a ringing key for said source normally connected to said switching mechanism, and supervisory means operated on connection of the switching mechanism with a busy line to automatically disconnect the source of ringing current, and 15 prevent the application of signaling current to a line already in talking condition.

16. In a telephone system, a plurality of lines extending by their limbs from 20 subscribers' stations to an exchange, a cord circuit at the exchange for connecting the lines, a source of signaling current at the exchange, a ringing key for connecting said source to the cord circuit, said springs normally connected to said cord circuit, a relay in said cord circuit adapted to be automatically operated when the cord is connected to a busy line to disconnect said normal connection between the switch springs and 25 the cord and to prevent application of the signaling current to a line already in talking condition.

17. In a telephone system, a plurality of telephone lines extending by their limbs 30 from substations to an exchange, switching mechanisms at the exchange for connecting the lines for conversation, a signaling circuit adapted to be manually connected to such switching mechanisms, and means for preventing the closure manually of such signaling circuit to one of such switching mechanisms when such switching mechanism is connected to a busy line.

18. In a telephone system, a plurality of 35 telephone lines extending by their limbs from substations to an exchange, switching mechanisms at the exchange for connecting the lines for conversation, a signaling circuit adapted to be manually connected to such 40 switching mechanisms, means for manually controlling the signaling circuit when the switching mechanism is connected to one of the lines in signaling condition, and means for preventing the closure manually of the signaling circuit when such line 45 is in talking condition.

19. In a telephone system, a plurality of telephone lines extending by their limbs 50 from substations to an exchange, cord circuits at the exchange for connecting the lines for conversation, a signaling circuit adapted to be manually connected to such 55 cord circuits, and independent means adapted to control the continuity of such signaling circuit, one of such means under the

control of an exchange operator to connect the signaling circuit to a cord circuit connected in signaling condition to one of the lines, and another of such controlling means under the control of the substation connected to such line. 70

20. In a telephone system, a plurality of telephone lines extending by their limbs from substations to an exchange, cord circuits at the exchange for connecting the 75 lines for conversation, a signaling circuit adapted to be manually connected to such cord circuits, a key associated with each of such cord circuits by which an exchange operator may complete the signaling circuit 80 to the corresponding cord circuit after such cord circuit has been connected with one of the lines in ringing condition, and means for preventing the closure of the signaling circuit by means of such key when such line 85 is placed in talking condition.

21. In a telephone system, a plurality of telephone lines extending by their limbs from substations to an exchange, cord circuits at the exchange for connecting the 90 lines for conversation, a signaling circuit adapted to be manually connected to such cord circuits, a key associated with each of such cord circuits by which an exchange operator may complete the signaling circuit to 95 the corresponding cord circuit after such cord circuit has been connected with one of the lines in ringing condition, and means for rendering such key inoperative when such cord is connected to a busy line. 100

22. In a telephone system, a plurality of telephone lines, a central station circuit adapted to connect said lines in circuit, a source of signaling current adapted to be connected to operate the signal at substations on said lines, circuit connections for connecting said source in circuit with said telephone line, means to prevent the connection of said source with a busy line, and a manual switch to connect the said source to 110 the said circuit connections, said manual switch being independent of the preventing means. 105

23. In a telephone system, a plurality of telephone lines extending by their limbs 115 from substations to an exchange, cord circuits at the exchange for connecting the lines for conversation, a signaling circuit adapted to be manually connected to such cord circuits, manual means associated with 120 each of such cord circuits for controlling the continuity of the signaling circuit thereto, and a supervisory relay for independently controlling the continuity of such signaling circuit. 125

24. In a telephone system, a plurality of telephone lines extending by their limbs 130 from substations to an exchange, cord circuits at the exchange for connecting the lines for conversation, a signaling circuit 135

- adapted to be manually connected to such cord circuits, manual means associated with each of such cord circuits for controlling the continuity of the signaling circuit there-
 5 to, and a supervisory relay for independently controlling the continuity of such signaling circuit through normally closed contacts operated by such relay.
25. In a telephone system, a plurality of telephone lines extending by their limbs from substations to an exchange, cord circuits at the exchange for connecting the lines for conversation, a signaling circuit adapted to be manually connected to such
 10 cord circuits, manual means associated with each of such cord circuits for controlling the continuity of the signaling circuit there-
 15 to, and a supervisory relay for independently controlling the continuity of such signaling circuit, the energizing winding of such relay being independent of the signaling circuit.
26. In a telephone system, a plurality of telephone lines extending by their limbs from substations to an exchange, cord circuits at the exchange for connecting the lines for conversation, a signaling circuit adapted to be manually connected to such
 25 cord circuits, and a non-marginal supervisory relay under the control of the called subscriber for interrupting the continuity of the signaling circuit.
27. In a telephone system, a plurality of telephone lines extending by their limbs from substations to an exchange, cord circuits at the exchange for connecting the lines for conversation, a signaling circuit adapted to be manually connected to such
 30 cord circuits, and a non-marginal supervisory relay adapted to interrupt the signaling circuit when the associated cord circuit is connected to a busy line.
28. In a telephone system, a plurality of telephone lines extending by their limbs from substations to an exchange, cord circuits at the exchange for connecting the lines for conversation, a signaling circuit adapted to be manually connected to such
 35 cord circuits, and a relay the contacts of which are in the signaling circuit, the energizing winding of such relay being in circuit with the connected line but not in such signaling circuit.
29. In a telephone system, a plurality of telephone lines extending by their limbs from substations to an exchange, cord circuits at the exchange for connecting the lines for conversation, a signaling circuit adapted to be manually connected to such
 40 cord circuits, and a relay the contacts of which are in the signaling circuit, the energizing winding of such relay being connected to one of the talking strands of the associated cord circuit.
30. In a telephone system, a plurality of telephone lines extending by their limbs from substations to an exchange, cord circuits at the exchange for connecting the lines for conversation, a signaling circuit adapted to be manually connected to such cord circuits, and a supervisory relay for controlling the continuity of such signaling circuit to one of the cord circuits when such cord circuit is connected to one of the lines, such relay connected so as to be operated by direct current.
31. In a telephone system, a plurality of telephone lines extending by their limbs from substations to an exchange, cord circuits at the exchange for connecting the lines for conversation, a signaling circuit adapted to be manually connected to such cord circuits, a first relay adapted to place a supervisory signal in condition to operate when the associated cord circuit is connected with one of the lines, and a second relay adapted to render such supervisory signal inoperative when the called subscriber responds, the energization of the first relay serving to close a break in the energizing circuit of the second relay and the energization of such second relay serving to interrupt the continuity of the signaling circuit to such cord circuit.
32. In a telephone system, a plurality of telephone lines extending by their limbs from substations to an exchange, cord circuits at the exchange for connecting the lines for conversation, a signaling circuit adapted to manually be connected to such
 45 cord circuits, a first relay connected to one talking strand of one of the cord circuits, and a second relay connected to the other talking strand of such cord circuit, the energization of the first relay serving to close a break in the energizing circuit of the second relay and the energization of such second relay serving to interrupt the continuity of the signaling circuit to such cord circuit.
33. In a telephone system, a plurality of telephone lines extending by their limbs from substations to an exchange, cord circuits at the exchange for connecting the lines for conversation, a signaling circuit adapted to be connected to such cord circuits, a key associated with each of such cord circuits by which an exchange operator may complete the signaling circuit to the corresponding cord circuit after such cord circuit has been connected with one of the lines in ringing condition, and a relay the contacts of which are in the signaling circuit, the energizing winding of such relay being in circuit with the connected line but not in such signaling circuit.
34. In a telephone system, the combination with a cord circuit, of a ringing key therefor, a supervisory relay, said ringing key being connected with a strand of the

cord circuit through normal contacts of said supervisory relay, substantially as described.

35. In a telephone system, the combination with a cord circuit, of a ringing key therefor, having a plurality of contacts normally in series with a portion of a talking strand of the cord circuit, a supervisory relay having contacts in the circuit of said key, said relay being actuated during conversation to disconnect said series key contacts from the talking circuit, substantially as described.

36. In a telephone system, the combination with a cord circuit, a ringing generator, a supervisory relay, the current from said generator being connected with the calling end of the cord circuit through normally closed contacts of said relay, substantially as described. 15 20

In witness whereof, I hereunto subscribe my name this 9 day of March A. D. 1908.
